US0D1108464S

(12) **United States Design Patent** (10) Patent No.: **US D1,108,464 S**
(45) Date of Patent: ** Jan. 6, 2026

(54) **DISPLAY SCREEN OR PORTION THEREOF
WITH GRAPHICAL USER INTERFACE**

(71) Applicant: **Apple Inc.**, Cupertino, CA (US)

(72) Inventor: **Nicholas Felton**, Sunnyvale, CA (US)

(73) Assignee: **Apple Inc.**, Cupertino, CA (US)

(**) Term: **15 Years**

(21) Appl. No.: **29/966,296**

(22) Filed: **Oct. 1, 2024**
